UNITED STATES PATENT OFFICE.

D. AZRO A. BUCK, OF WATERBURY, CONNECTICUT, ASSIGNOR TO THE
WATERBURY WATCH COMPANY, OF SAME PLACE.

WATCH-MOVEMENT.

SPECIFICATION forming part of Letters Patent No. 293,143, dated February 5, 1884.

Application filed September 10, 1883. (No model.)

To all whom it may concern:

Be it known that I, D. AZRO A. BUCK, of Waterbury, in the county of New Haven, and in the State of Connecticut, have invented certain new and useful Improvements in Watch-Movements; and I do hereby declare that the following is a full, clear, and exact description thereof, reference being had to the accompanying drawings, making a part of this specification, in which—

Figure 1 is a perspective view of the pillar-plate, top plate, balance-bridge, and winding-bridge separated from each other. Fig. 2 is a like view of said parts combined, and Figs. 3 and 4 are respectively sections upon lines *x x* and *z z* of Fig. 2.

Letters of like name and kind refer to like parts in each of the figures.

The design of my invention is to simplify the construction, to increase the efficiency, and to lessen the expense of watch-movements, to which end it consists, principally, in a winding-bridge which is adapted to confine in place the winding-pinion, to support the balance-bridge, and to act as a pillar between and in connection with the pillar-plate and the top plate, substantially as and for the purpose hereinafter specified.

It consists, further, in the construction of the winding-bridge and its combination with the top and pillar plates and the balance-bridge, substantially as and for the purpose hereinafter shown.

In the annexed drawings, A represents the pillar-plate of my watch, which has the usual form, and is adapted to receive the time-train. At a suitable point adjacent to the winding-train said plate is provided with a recess, *a*, that corresponds to a winding-pinion, B, and forms one-half of a bearing for the same, while at points substantially equidistant from each other and from said recess two pillars, *a'*, are secured within said plate, near its periphery.

Fitted upon the plate A, between the balance-recess and the spring-barrel, is a winding-bridge, C, which has preferably the general shape shown in Fig. 1, its outer edge extending nearly to and having the curve of the edge of said plate, while its side edges con-

form to the circles of said balance-recess and winding-barrel, and within its inner face is provided a recess, *c*, that corresponds to the recess *a* of said plate A, and in connection therewith forms a bearing for the winding-pinion B. The winding-bridge C is preferably provided with one or more dowel-pins, *c'*, which fit into corresponding holes, *a'*, in the plate A, and operate to insure the relative lateral positions of said plate and bridge; but, if preferred, said pins may be omitted, and any other usual means may be employed for securing the result named. The thickness of the bridge C corresponds to the height of the body of each pillar *a'*, and upon the latter and said bridge is placed a top plate, D, which is held in place by means of two screws, *d*, that pass through the same into said pillars, and a screw, *d'*, which passes through said plate D and said bridge C, and has its threaded end contained within the pillar-plate A, said last-named screw thus operating to confine said parts in relative positions. The top plate, D, extends more than one-half the distance across the winding-bridge C, and upon the remaining portion of the latter is placed a balance-bridge, E, which is preferably doweled thereon, and is secured in position by means of a screw, *e*, that passes through said balance-bridge into said winding-bridge, or through the latter into the plate A, as may be preferred.

In consequence of the attachment of the balance-bridge E to the winding-bridge C, instead of to the pillar-plate A, said balance-bridge may be constructed from a thin plate of metal, and therefore is more easily made and more readily handled in setting up or taking down the watch than when constructed in the usual form, while from the form of said winding-bridge and its combination with said pillar-plate and the top plate, D, greater strength is secured, a less number of parts is required, and the cost of the watch is lessened.

Having thus fully set forth the nature and merits of my invention, what I claim as new is—

1. A winding-bridge which is adapted to confine in place the winding-pinion, to support the balance-bridge, and to act as a pillar be-

tween, and in connection with the pillar-plate and the top plate, substantially as and for the purpose specified.

2. The combination of the pillar-plate A, provided with the recess *a*, the winding-pinion B, the winding-bridge C, having the recess *c*, and the top plate, D, substantially as and for the purpose shown.

3. In combination with the balance-bridge E, the winding-bridge C, secured upon the pil-

lar-plate A, substantially as and for the purpose set forth.

In testimony that I claim the foregoing I have hereunto set my hand this 20th day of May, A. D. 1883.

D. AZRO A. BUCK.
